UNITED STATES PATENT OFFICE

171,673

COMBINED ASH TRAY AND PLANT HOLDER

Robert E. Williams, San Diego, Calif.

Application October 20, 1953, Serial No. 27,250

Term of patent 14 years

(Cl. D85—2)

To all whom it may concern:

Be it known that I, Robert E. Williams, a citizen of the United States, residing at San Diego, in the county of San Diego, and State of California, have invented a new, original, and ornamental Design for a Combined Ash Tray and Plant Holder, of which the following is a specification, reference being had to the accompanying drawing, forming part thereof.

Fig. 1 is a top plan view of a combined ash tray and plant holder, showing my new design.

Fig. 2 is a side elevational view thereof, and

Fig. 3 is a vertical cross-sectional view taken on line 3—3 of Fig. 1.

The broken line showing of legible matter in Fig. 1 is for illustrative purposes only.

I claim:

The ornamental design for a combined ash tray and plant holder, as shown and described.

ROBERT E. WILLIAMS.
